TREATMENT OF HYDROCARBON OILS

Jacque C. Morrell, Chicago, Ill., assignor to
 Universal Oil Products Company, Chicago, Ill.,
 a corporation of South Dakota

No Drawing. Application January 11, 1932,
 Serial No. 586,077

3 Claims. (Cl. 196—36)

This invention relates to the treatment of hydrocarbon oils, and refers more particularly to the treatment of lower boiling motor fuel fractions produced in the conversion of high boiling hydrocarbon mixtures at elevated temperatures, though analogous fractions produced from other sources may also be treated.

More specifically the invention has reference to a refining process capable of controllably reducing the percentages of highly unsaturated gum-forming components and the sulfur content respectively of hydrocarbons to a point consistent with the requirements of commercial specifications, the process disclosed being one of wide application.

Various attempts have been made from time to time to improve upon the established and generally utilized method for the production of salable motor fuels from the raw distillates produced in cracking operations, this method consisting of regulated treatments with chemicals chief of which is sulfuric acid of commercial grade, followed by neutralizing and redistillation to any desired end point. However, none of the treatments thus far proposed for producing treating effects upon such distillates in heated vaporous condition has been commercially economical. The present invention accomplishes these ends by a new and novel process which will be hereinafter fully disclosed.

In one specific embodiment the invention comprises treatment of hydrocarbon oil vapors, particularly cracked hydrocarbon oil vapors, with oxidizing gases in the presence of suitable catalytic and/or adsorbent contact materials in a primary stage and the further treatment of the vapors with sulfuric acid solutions containing dissolved salts or other equivalent diluent or spacing materials.

To produce the oxidation reactions characteristic of the first stage of the treatment any oxygen-containing gas mixture, such as air, or such gases as oxygen or ozone may be employed alone, or in admixture with diluent or relatively inert gases such as steam, carbon dioxide, nitrogen, et cetera, or different oxidizing gases may be used in combinations suitable for producing desired effects. While in the majority of instances air is sufficiently active for producing the treating effects characteristic of this stage, the effect of the oxygen contained therein may be augmented by the addition of oxygen to produce a mixture containing an excess over the percentage normal to the atmosphere or air may be ozonized by the usual method of subjecting it to the action of

electrical discharges. In any event the amount and character of oxidizing gas employed will be so regulated that the reactions produced are at all times within the control of the operator.

To further assist in controlling the rate and character of the oxidation processes various contacting materials may be employed, these being classifiable broadly as follows:

1. Metals,	65
2. Metal oxides,	65
3. Salts of metals, and	65
4. Adsorbent materials usually of a non-metallic or siliceous character.	65

As metals which may be used as contact materials to assist in the oxidation reactions may be mentioned such metals as iron, aluminum, zinc, tin, nickel, cobalt, copper, lead, mercury, calcium, barium, strontium, cadmium, molybdenum, tungsten, chromium, vanadium, et cetera, such metals being utilizable either singly or in suitable combinations or alloys although not with equivalent efficiencies.

As oxides, the corresponding oxygen compounds of the metals disclosed in the previous paragraph may be employed, and at times the oxides corresponding to the different degrees of valence of the metals may be utilized to advantage. For example, either ferrous or ferric oxide may be employed or the various oxides of chromium. In some instances mixtures of metals and oxides may be employed, which mixtures correspond to either a low degree of oxidation or a partially reduced oxide.

Under the heading of metal salts are employed preferably those that are not materially effected by contact with the mixture of oxygen-containing gases or the oil vapors. While in most cases it may be sufficient to use the commoner salts of metals such as sulfates, chlorides, nitrates, phosphates, acetates, etc., other less common salts may be employed such as the chromates, permanganates and iodates, oxidizing salts of this character sometimes assisting in producing the preliminary oxidations characteristic of the process, the addition of the oxidizing gases then serving to maintain the state of oxidation of the salt. Salts may be used in various admixtures and also in admixture with the metals and metal oxides mentioned in the two preceding classes, each mixture producing characteristic results.

Various contact materials of the adsorbent character mentioned above as class 4 may be employed, such materials including fuller's earth, bentonite, bauxite, zeolites, activated carbons, 110

et cetera, which may be used singly or in combinations either among themselves or with the metallic compounds of the first three classes, in which case they may act as vehicles for their support or as spacing means. Thus, in some cases solutions of metallic salts may be incorporated with the adsorbent material, the solvent being driven off by heating, the salt brought to the oxide condition by calcination and reduced to metal by means of hydrogen or other reducing gases, though the operation may also stop at the production of the salt or the oxide.

In place of materials of a distinctly adsorbent character, relatively inert spacing materials may be used such as fire-clay, pumice, silica fragments, et cetera.

To summarize, the effect of the reactions of the first stage is generally to oxidize and/or cause the polymerization of highly unsaturated hydrocarbons and sulphur compounds so that high molecular weight aggregates may be produced, these reactions being continued by the treatments of the second stage to be presently described so that the net result is the elimination of the undesirable constituents to any desired extent. It will be evident that owing to the widely varying composition and complicated chemical nature of the hydrocarbon oil mixtures which may be subjected to the treatment that the exact nature of the treating reactions will vary markedly, and in some cases they may be of an extremely complex character.

In the second stage of the process the vapors after the preliminary oxidizing treatment are further subjected to the action of what may be termed "spaced" sulfuric acid solutions to complete the treatment. Such treating solutions are made by using soluble compounds, particularly sulfates and acid sulfates, in solution with sulfuric acid. The treating effect of these solutions may be considered to be substantially equivalent to the effect which would be produced by the use of aqueous sulfuric acid solutions of similar concentrations, though it is manifestly impossible to maintain such dilute solutions under the conditions of temperature and pressure under which vapors of gasoline boiling point range exist. When attempts are made to use such dilute aqueous solutions the acid is rapidly concentrated by the evaporation of the water to a strength which in practically all cases produces heavy treating effects accompanied by charring and carbonization of the hydrocarbons. By using dissolved compounds of a substantially neutral character and having a low vapor pressure, the concentration of sulfuric acid solutions may be maintained at a concentration low enough to produce desirable treating effects without undue side reactions and unnecessarily high losses.

While the sulfates and acid sulfates of the alkali, alkaline earth and heavy metals may be advantageously employed in solutions of the type described, other compounds such as neutral, acidic or basic organic materials may be used as described in a number of my copending applications.

To summarize, the net effect of the two-stage treatment is the controllable elimination of highly unsaturated olefinic constituents responsible for the gum formation and the reduction of the total sulphur content to a percentage meeting commercial specifications.

75 The two stages of the treatment may be con-

ducted in any type of apparatus suitable for effecting intimate contact of the reacting constituents and providing a sufficiently long time factor. In the primary or oxidizing stage the oxidizing gas may be injected into the vapors to be treated and the mixture then passed over the solid contact material supported in some type of treater such as, for example, a vertical cylindrical tower which supports the solid contact materials on a perforated false bottom.

In the second stage of the treatment, the sulfuric acid solutions may be introduced at the top of a treating tower filled with baffling or spacing material and allowed to flow downwardly countercurrent to the ascending stream of vapors. Sludge materials and heavy hydrocarbon oil mixtures accumulating as liquids in the bottom of such a treater may be removed and separated, the spent treating reagents being either wasted or regenerated in suitable steps and continuously returned to the treater in lieu of fresh solution.

It will be obvious to those conversant with the types of treatment described that the use of filtering or settling devices may be necessary in case the treated vapors contain suspended or entrained particles of liquids or solids and that if necessary they may be subjected to further treating steps such as, for example, neutralization with ammonia or alkaline solutions.

As a characteristic example of results obtainable by the application of the process of the invention to the treatment of cracked vapors, an example may be chosen in which the vapors arise from the fractionator of a cracking plant operating upon heavy California distillates as charging oil.

Such vapors at the temperature and pressure normal to the primary fractionator of the plant, to-wit, 520° F. and 225 pounds per square inch may be passed in the primary oxidizing stage over a mixture of lime and ferric oxide mixed with fairly coarse fuller's earth to assist in extending the contact surfaces. Air may be added to the vapors prior to their passage through the oxide bed in amounts approximating twenty cubic feet per barrel of fractionated and condensed gasoline from the process.

After this preliminary oxidizing treatment the vapors may be further acted upon by an aqueous solution of sulfuric acid and sodium acid sulfate by flowing the solution downwardly in a filled treating tower countercurrent to the ascending vapors. The composition of the treating solution may be approximately as follows by weight: 130 sulfuric acid, 50%; sodium acid sulfate, 25%; water, 25%. By using this solution in the proper amount to constitute a treatment equivalent to the use of five pounds of sulfuric acid per barrel of finished gasoline and reducing the pressure and temperature somewhat, the degree of refinement of the gasoline produced by fractionating the vapors to a desired end point may be brought to a point consistent with the commercial requirements in finished gasoline with perhaps a 140 light caustic wash as a final treatment.

The following tabulation indicates a triple comparison between (1) the gasoline produced by simple fractionation without vapor phase treatment of any kind, (2) gasoline produced by a vapor phase treatment with sulfuric acid containing sodium acid sulfate, and (3) combination vapor phase treatment with mild oxidation in the first stage as described, followed by treatment

with the sulfuric acid reagent in the vapor phase and final fractionation:

	1	2	3
5 Gravity ° A. P. I.....	54.7	54.9	55.0
End boiling point.....	420	418	415
Color, Saybolt.....	4	30	30
Mg. gum by copper dish method.....	390	40	10
Total sulfur °.....	0.45	0.3	0.07

10 Thus, it is pointed out that while distillation to end point gasoline is not effective in producing a product of good color, low gums and low sulfur, and the sulfuric acid reagent alone causes insufficient reduction in sulfur and gums, the combination of oxidation and sulfuric acid treatment in vapor phase produces all of the desired results. This may be explained by the removal of oxidation products of sulfur in the final treatment which otherwise would not be removed. The invention may be applied equally as well to very high sulfur stocks, such as those from California, Oregon Basin, Venezuela, Mexico and the like.

15 25 The oxidizing step is of a relatively simple character and presents no special difficulties so that its use in combination with the spaced sulfuric acid reagents makes possible the economical production of a high grade gasoline and thus constitutes a distinct improvement over processes in use at the present time.

30 35 While the foregoing description and example are sufficient to describe the invention and indicate its merits, the invention is not limited to the precise descriptive details or the numerical example.

I claim as my invention:

1. In the art of refining the overhead products

resulting from the cracking of hydrocarbon oil and comprising a mixture of saturated and unsaturated hydrocarbons of different boiling points within the motor fuel range, the improvement which comprises subjecting said overhead products in heated vaporous condition first to the action of a free oxygen-containing gas in the presence of a solid contact agent and thereafter while still in heated vaporous condition subjecting said overhead products to the action of an aqueous solution of sulfuric acid containing a dissolved salt.

2. In the art of refining the overhead products resulting from the cracking of hydrocarbon oil and comprising a mixture of saturated and unsaturated hydrocarbons of different boiling points within the motor fuel range, the improvement which comprises subjecting said overhead products in heated vaporous condition first to the action of a free oxygen-containing gas in the presence of a solid contact agent and thereafter while still in heated vaporous condition subjecting said overhead products to the action of an aqueous solution of sulfuric acid containing a dissolved salt of an alkali metal.

3. In the art of refining the overhead products resulting from the cracking of hydrocarbon oil and comprising a mixture of saturated and unsaturated hydrocarbons of different boiling points within the motor fuel range, the improvement which comprises subjecting said overhead products in heated vaporous condition first to the action of air in the presence of a metal oxide and thereafter subjecting said overhead products while still in heated vaporous condition to the action of an aqueous solution of sulfuric acid containing a dissolved salt of an alkali metal.
